UNITED STATES PATENT OFFICE.

CHARLES C. RUEGER, OF BENICIA, CALIFORNIA.

ORE-CONCENTRATOR.

1,387,075.

Specification of Letters Patent. Patented Aug. 9, 1921.

Application filed September 6, 1919. Serial No. 322,112.

To all whom it may concern:

Be it known that I, CHARLES C. RUEGER, a citizen of the United States, residing at Benicia, in the county of Solano and State 5 of California, have invented certain new and useful Improvements in Ore-Concentrators; and I do hereby declare the following to be a full, clear, and exact description of the invention, such as will enable others 10 skilled in the art to which it appertains to make and use the same.

My invention relates to that class of concentrating apparatus which is used for the treatment of ore material commonly designated in the art as "sand." It is of the type 15 of concentrators known as bateas or pans, and embodies some features common to mechanisms of that type, but differs from the known forms in several important features and particulars.

The invention consists in the novel features hereinafter described in detail in connection with the accompanying drawings, and more particularly pointed out in the ap- 20 pended claims.

Referring to the drawings:

Figure 1 is a top plan view of the apparatus, with certain parts omitted for the purpose of clearness.

Fig. 2 is a vertical partly sectional view 30 taken through the center of the pan.

Figs. 2^a and 2^b are enlarged views of de- tails.

Fig. 3 is an enlarged detail sectional view 35 of the peripheral trough and one of the outlets for the heavier concentrates.

Fig. 3^a is a section taken on line *a*—*b* of Fig. 3.

Figs. 4 and 4^a illustrate radial vertical 40 sections of modified forms of pans.

Figs. 5 and 5^a show detail views from two sides of the cam mechanism for imparting oscillations to the pan.

Figs. 6 and 6^a show a detail side view 45 and a detail partly sectional view at right angles to the other, of the recoil mechanism for returning the pan to normal position and imparting impacts to it.

Fig. 7 illustrates a modified mechanism 50 for feeding ore pulp into the separating pan.

The most essential part of my apparatus 55 is a shallow pan, preferably made of cast iron or of pressed sheet steel, circular in form, as shown in top view Fig. 1; its form in vertical and radial cross section along line

G, A, A, G, of Fig. 1 being shown by the heavy black line in Fig. 2, also modifications of form in Figs. 4 and 4^a. The pan being circular, all similar sections through 60 its center present practically identical forms. It will be noticed that the deepest part of the pan is along a circular valley or line C about half way between the rims or ridges A and D, and that the pan bottom rises in 65 regular gentle slopes E and F from C to A and D. Rim or ridge D is at a higher level than rim or ridge A and slope F is steeper than slope E. This may be the preferable 70 arrangement of the slopes but I am aware that other pitches may be employed without departing from the invention.

Surrounding the peripheral rim D is a 75 circular trough G divided into two compartments by means of a central annular rib G⁴. In this rib are located several outlet tubes H and H' passing out through the bottom of the trough G. One of the outlet tubes is illustrated in Fig. 3. The pan is attached at its center to a funnel shaped casting B' 80 having a tubular outlet B, which outlet is pivotally mounted in the tubular socket standard and base plate I. This socket base plate is fastened adjustably to another base plate J, which latter is firmly attached to 85 foundation timbers K. An outlet tube L extends from the plate J and the tubular outlet B to the tailings trough M.

The peripheral rim D of the pan is set 90 absolutely level by means of adjusting screws J', provided in the base plate I, before this plate is bolted permanently to its foundation plate J. The pan, thus supported and pivoted at its center, is given a horizontal vibratory or vanning movement by a 95 mechanism located at one side near the peripheral trough G. The vibration must be differential, *i. e.* more rapid in one direction than the reverse, and may or may not end in percussion or shock. This can be accomplished in several known ways. The mechanism chosen, and illustrated here in Figs. 2-5, 5^a, 6 and 6^a for this purpose, consists of a cam O actuated by a shaft *b* provided with fast and loose belt pulleys N and N'. 100 The cam has two cam faces *a*, *a*, Fig. 5^a, alternately engaging with a tappet *c*, projecting vertically from the bottom of the trough G. This tappet *c* has an arm *d* secured to the pan by screws *e*. The thrust of the cam is 105 horizontal, as shown by the arrow in Fig. 5 and tangential to the pan circle. The recoil

of the pan is effected by a coil spring *f*, Fig. 6, which is attached at one end to an arm *g* secured by screws *n* to the trough *G*, and the other end of the spring is provided 5 with a bolt and nut *i* secured to a bracket *h* on the block *P*. There is provided, also, a shock or percussion device consisting of a tappet *m* secured to the underside of the pan, which engages a percussion block *k* 10 adjustable tangentially to the pan periphery by means of the screw bolt *l*.

There must also be provided means for feeding the ore pulp uniformly to the concentrating pan. Fig. 2 shows in elevation, 15 and partly sectional, the device which I have contrived for this purpose. It consists of a feed launder *Q* containing at its outlet a screen *Q'* (shown diagrammatically) for arresting fibrous and other undesirable matter. The launder discharges 20 through the screen into the rotatable hopper *R*, from which a number of pipes *R'*, provided with suitable nozzles, distribute the ore pulp into the pan. As best shown in 25 Figs. 2, 2^a and 2^b the nozzle *R''* of the pipes *R'* are flattened to present a rectangular cross section, which nozzles discharge in spreading jets onto horizontal spreader plates *R¹²* that deliver the feed material in 30 thin sheets at the surface only and tangentially to the pan contents. The hopper *R* is adjustably supported by means of a bolt *R³*, which passes through a sleeve *R²* and is provided with a nut *R⁴*. By turning the 35 nut *R⁴*, the hopper and its attachment may be raised or lowered. To insure regular and uniform distribution of the ore pulp around the whole circumference of the pan, the hopper *R* and its distributing pipes are 40 rotated by means of a cord drive from cam shaft pulley *S*, Figs. 1 and 2. Instead of the pipes a cone *Y* Fig. 7 attached to the hopper *R* and rotating with it, can be used as the distributor of the ore pulp. The ore 45 pulp passes from the hopper *R* into the cupped apex *X* of the cone *Y*, thence it flows over the top edge of the cone and spreads evenly over its surface, discharging 50 into the pan at the periphery or base of the cone in a thin sheet, the aim always being to combine uniform distribution of the feed with a minimum disturbance of the ore pulp in the pan. With the latter end in view, the nozzle of the distributing pipes, 55 or the peripheral edge of the cone, is submerged slightly in the pulp occupying the pan, which effects a rotary drag to the pan pulp, and gives the tailings a spiral path to the central discharge instead of the 60 shorter radial one to the ridge *A*, and consequently increased opportunity for separation of the valuable mineral is provided.

Having described the construction, I will now describe the action or operation of the 65 pan. The ore pulp having filled the pan

while said pan is in vibratory motion, the latter will retain the sand particles in semi-suspension, permitting their more or less free movement. This causes the particles to stratify according to their specific gravity, 70 the heaviest and densest settling to the bottom and accumulating especially at the lowest level or valley *C*, while the lightest particles will accumulate near the surface, where they will form a slope toward the 75 central discharge rim *A*, over which they are carried by the flow of water aided by the vaning motion of the pan. The level of the discharge rim is variable by means of an adjustable ring, shown at *A*, *A*, Fig. 2, 80 which can be raised or lowered to regulate the centripetal flow of the water and tailings into the discharge funnel, from which they pass down through the pipe *B* and *L* into the waste launder *M*, and are carried 85 by the latter to further treatment or to the waste dump. Any valuable minerals separating from the tailings on their way to the overflow rim *A* settle on the slope *E* and gravitate back toward the lowest level *C* of 90 the pan.

When the heavier mineral particles (concentrates) have settled on the pan bottom, they come under the influence of centrifugal force induced by the oscillating motion of 95 the pan, and tend to move radially up the slope *F*. At the same time the differential motion of the pan, especially if ending in percussion, will move the concentrates tangentially. The resultant travel of the particles will be diagonally up the slope *F* along lines dependent on many factors which need not be considered here, but ending in any case by discharge over the 100 peripheral edge *D* into the trough *G*. To further clean the concentrates from the entangled inferior matter, clear water is run into trough *G* from the perforated supply pipe *T* in such quantity that a current of water toward the center of the pan is produced which effects cleaning as it meets the flow of concentrates passing outward over rim *D*. 105

The concentrates, having arrived in trough *G* are subjected to the maximum 115 motion of the pan, which again stratifies them according to their specific gravity, the heaviest accumulating in the inside compartment *G'*, the lighter flowing over the dividing rib *G⁴* into the outside compartment *G''* 120 of trough *G*.

An enlarged illustration of trough *G* is given in Fig. 3 to facilitate a description of the further course of the concentrates. As already stated, the heavier concentrates 125 settle into the inner compartment *G'*, whence the percussive action of the pan, especially, will transport them along the trough to the discharge tubes *H*. The discharge is automatically regulated by a device illustrated 130

in Figs. 3 and 3^a. The discharge tube H communicates with the outside by passing through the bottom of trough G. Half of the top of the tube is cut off slanting toward compartment G'; the remaining top is covered by a suitably formed L-shaped apron of sheet metal U fastened to the top of the rib G⁴ with screws. This apron is so made, as shown in Fig. 3^a, that it shuts off the 10 passage to the top of the tube H on all sides except around the lower edge of the apron. Thus the concentrates are compelled to travel the course indicated by the dotted arrow from D to the outlet of the tube H. 15 The actual discharge of the concentrates is regulated by caps V screwed onto the outlet of the tube H, said caps being perforated to suit the requirements. If desired, however, some other discharge regulating device 20 may be used.

The lighter concentrates flowing into the trough compartment G'' are discharged through a similar device provided at outlet tubes H', (Fig. 1) the parts above described 25 being suitably arranged therefor. The concentrates are delivered by the tubes into receptacles W (Fig. 2), or drop into launders which carry them to conveniently placed storage tanks.

30 Fig. 4, shows a pan in which the valley C¹⁰ is flat, while Fig. 4^a shows the valley C²⁰ as forming a segment of a curve extending from A to D.

It is obvious that various modifications 35 can be made in the herein described apparatus, and in the construction, combination and arrangement of parts, which can be used without departing from the spirit of my invention.

40 What I claim and desire to secure by Letters Patent is:—

1. An apparatus for concentrating ore sand, comprising a circular pan having a circular central rim for the discharge of 45 tailings or waste, and a circular peripheral rim for the discharge of concentrates, the lowest or deepest part of said pan being located along a circular channel intermediate and concentric to the said discharge rims, 50 the pan bottom rising from said lowest level by concentric slopes to said central and peripheral discharge rims, means for oscillating said pan, and a pulp feeder for said pan.

2. A concentrating pan of the kind described in claim 1, pivoted on a tubular central axis serving as a tailings conduit, said axis resting rotatably in a socket having a base plate attached to it, leveling screws in said base plate by which the discharge rims 55 of the pan can be set level, and other screws by which said base plate can be connected with a foundation plate and fastened to foundation timbers.

3. A concentrating pan of the kind defined in claim 1, having a peripheral trough

to receive the concentrates discharging over the peripheral rim, said trough being divided into two concentric compartments and having automatic discharge devices from said compartments to the outside of the pan. 70

4. A concentrating apparatus of the kind defined in claim 1, in which the mechanism imparting an oscillating movement to said pan includes elements for producing differential oscillations, to impart upward travel 75 to the concentrates from the lower level of the pan toward the peripheral rim.

5. A concentrating apparatus of the kind defined in claim 1, in which the mechanism for imparting oscillating movement to said pan is combined with means for imparting shocks to the pan at the end of each oscillation to impart upward travel to the concentrates from the lower level of the pan 80 toward the peripheral rim. 85

6. A concentrating apparatus of the kind defined in claim 1, in which the mechanism imparting oscillating movement to the pan includes elements for producing differential oscillations, to cause upward travel of the concentrates from the lower level of the pan 90 toward the peripheral rim, and means for imparting shocks to the pan at the end of each oscillation, to accelerate this upward travel. 95

7. A concentrating apparatus comprising a horizontally oscillating circular pan having an annular central rim for the discharge of tailings or waste and a circular peripheral rim for the discharge of concentrates, the lowest or deepest part of the pan being located along a circular channel intermediate and concentric to the said discharge rims, the pan bottom rising from said channel by concentric slopes to said central and peripheral discharge rims, means for oscillating the pan, means for imparting a shock to the pan at the end of each oscillation, a peripheral trough arranged at the circumference of the peripheral rim and adapted to receive the concentrates passing over said rim, means for automatically discharging concentrates from said trough, and a feed launder discharging into a revolving hopper, distributing means depending from the hopper and adapted to deliver pulp at or below the level of the pulp occupying the pan. 100 110 115

8. The combination with a circular ore separating or concentrating pan having a peripheral trough provided with an annular vertical partition, of a plurality of discharge tubes extending vertically through said partition and through the bottom of the trough, for automatically discharging concentrates from said trough, the receiving upper ends of said tubes being partly covered by L-shaped aprons and partly open on the sides, the horizontal portions of said aprons resting on and being fastened to the 120 125 130

upper edge of said annular partition, the approximately vertical portions of said aprons extending downwardly along side of the tubes and closing against the annular 5 partition, the lower edges of the vertical portions of the aprons being below the receiving upper ends of the tubes, so that the

concentrates will have to pass to the receiving end of the tubes through an opening located at a lower level, and means for regulating the discharge at the lower ends of the tubes. 10

In testimony whereof I affix my signature.
CHARLES C. RUEGER.
